CLAIM

The ornamental design for an outsole, as shown and described.

DESCRIPTION

FIG. 1 is a lateral side view of the outsole;

FIG. 2 is a top view thereof;

FIG. 3 is a medial side view thereof;

FIG. 4 is a front view thereof;

FIG. 5 is a rear view thereof;

FIG. 6 is a front perspective view from the lateral side thereof; and,

FIG. 7 is a rear perspective view from the lateral side thereof.

Short, broken lines shown in the drawings of the outsole illustrate the environment of the claimed design or stitching and form no part of the claimed design.

1 Claim, 7 Drawing Sheets# US D939,813 S
